(57) CLAIM

I claim the ornamental design for a pad holder, as shown.

DESCRIPTION

FIG. 1 is a perspective view of a pad holder showing my new design;

FIG. 2 is a left side elevation view thereof;

FIG. 3 is a right side elevation view thereof;

FIG. 4 is a front elevation view thereof

FIG. 5 is a rear elevation view thereof;

FIG. 6 is a top elevation view thereof; and,

FIG. 7 is a bottom view thereof.
